UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

CAR CONSTRUCTION.

1,256,159.

Specification of Letters Patent. Patented Feb. 12, 1918.

Application filed November 4, 1916. Serial No. 129,599.

To all whom it may concern:

Be it known that I, ALLEN E. OSTRANDER, residing at Ridgewood, Bergen county, State of New Jersey, and being a citizen of the 5 United States, have invented certain new and useful Improvements in Car Construction, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

20 Figure 1 is a partial plan view of the underframe including the invention;

Figs. 2 and 2^a represent, respectively, a central vertical longitudinal sectional view and a side elevational view, in continuation 25 of the disclosure of Fig. 2;

Fig. 3 is a transverse sectional view, the section being taken on line 3--3 of Fig. 1 looking toward the bolster;

Fig. 4 is a transverse sectional view, the 30 section being taken on line 4--4 of Fig. 2^a;

Fig. 5 is a fragmentary view showing in elevation some of the parts in immediate proximity to the cross bearer of Fig. 4, which latter is shown in vertical section, the 35 section being taken on line 5--5 of Fig. 4;

Fig. 6 is an elevational view of a floor beam showing, in transverse section, one each of the center and side sills;

Fig. 7 is a detached fragmentary sectional 40 view of one of the side sills or side rails; taken on line 7--7 of Fig. 1;

Fig. 8 is an enlarged plan view of the bolster-center-filler-casting hereinafter referred to with fragments of the center and 45 side sills and bolster attached thereto; and

Fig. 9 is a central longitudinal sectional view, the section being taken on line 9--9 of Fig. 8.

The object of the invention is to produce 50 a railway car underframe of the trussed type, utilizing old railway rails for center and side sills and with bolsters, draft sills and end sills of the conventional type.

The underframe is of a trussed type comprising, intermediate the bolsters, a plural-

ity of railway rails, a plurality of truss rods and anchors therefor, with suitable struts co-operating therewith, together with side sills in a plane higher than that of the center sills and preferably supported by cross bearers carried by the center truss formation intermediate the bolsters, thereby obviating the necessity for using truss rods, except within the zone of the center sill construction.

65

Referring to the parts, 1 indicates railway rails which may be, and preferably are, rails which have been so worn in service as to be condemned for use where originally contemplated. These old rails have been re-rolled and placed in other service, but are commonly sold by the railroad companies for scrap, and, at scrap value, are more economical to use as herein shown and described than are rolled commercial shapes, 75 such as channels, Z's, etc. Intermediate the bolsters and end sills the underframe may be said to be of conventional form comprising Z-shaped draft sills 2, end sills 3, diagonal braces 4 and draft sill cover plate 5, together with suitable striking castings 6 and connection brackets 7 and 8.

70

The bolster 9 is preferably of the built-up type comprising diaphragms 10 of pressed metal extending from the zone of connection 85 with the draft sills outwardly beyond the side sills 11. The diaphragms 10 are provided with a circumscribing flange 12 with which are connected the top and bottom-cover plates 13 and 14, and also serve as a 90 means for connecting to the bolster the jacking plate 15.

80

The bolster-center-filler-casting is of peculiar formation and will be hereinafter specifically described, though it will be noted 95 that said bolster-center-filler-casting 16 extends rearwardly, that is, toward the middle of the car, and is provided with brackets 17, in which are anchored the ends of the trussed rods 18, the rails 1, 1, and the draft 100 sills 2 being also connected with said filler-casting.

Intermediate the bolsters cross bearers 20 are provided, which cross bearers are practically combination queen posts and cross 105 bearers and serve as means for contributing to the support of the center sills and the side sills as follows:

The truss rods 18 support the struts 21 upon which in turn rest said cross bearers 20 110

which comprise the filler-castings 22 which rest intermediate the struts 21 and the sills 1. Coöperating with the filler-castings 22 are diaphragms 23 which extend outwardly 5 from the sills 1 below and beyond the side sills 11. The cross bearers include one of said diaphragms 23 at each side of the center sills and said diaphragms are connected by a top tie plate or cover plate 24 riveted to outwardly extending flanges 25 of said diaphragms and are also connected by the compression member 26 which it will be noted is of angle form, having its vertical leg 27 riveted directly to the web of the diaphragm 23, the 10 horizontal outstanding leg 28 of said angle 26 extending between the struts 21 and the filler-casting before referred to, and the rivets 29 extending through said flange 28, and through a flange 30 of the strut 21. The 15 filler 22 is provided with an outstanding flange 22^a which rests in under, and is secured by direct rivet connection with, the bottom flanges of the rails 1, as best shown in Figs. 4 and 5.

20 In addition to the connections described, the cross bearer is also connected with a vertical web 33 of the strut 21 by rivets 34, thereby providing a strut coöperating with the center sills having wing portions extending 25 transversely of the car under the side sills, so as to support portions of said side sills intermediate the bolsters.

25 Intermediate the cross bearers, floor beams 35, of somewhat lighter construction, are employed, said floor beams including a compression member 36 comprising a commercially rolled angle member, a top plate 37, end fillers 38, which are riveted directly to the members 36 and 37, and intermediate 30 fillers 39 which are riveted to said members 36 and 37, and are also connected with the webs 40 of the rails 1 before referred to.

35 The side sills 11 may continue from end sill to end sill, though for convenience they 40 are intermittent in proximity to the bolsters, as shown, where said rails are spliced.

45 Referring now to the bolster-center-filler-casting 16, it will be noted that the usual king pin socket 50 is provided and vertical 50 walls 51 extend upwardly at each side of the middle portion of said casting to serve as a means of connection for an inner portion of the draft sills 2, which draft sills are connected by means of the rivets 52 with said 55 vertical walls 51. The casting extends rearwardly of the bolster proper and in addition to the bracket 17, before referred to, said casting comprises a shelf 53 upon which rest the end portions of the rails 1 and, extending 60 parallel with the web portions 40 of said rails, said casting is provided with integral ribs 54 which parallel and lie preferably in contact with said webs 40 so as to permit a direct rivet connection between the rails 1 and said ribs 54, as shown, and to stiffen the 65 rearwardly extending bracket portion of said casting, a centrally disposed vertically extending rib 55 is provided which rests between the rails 1 in the assembled structure. It will be noted that the ribs 54 are in approximate alinement with the line of greatest buffering stresses and to utilize the rails 1 to the best advantage to resist such buffering stresses, said rails, comprising portions of the center sills, are positioned, as shown, in a plane relatively lower than the plane of the rails 11, comprising the side sills, it being understood that the neutral axis of the rails 1 is preferably alined with that portion of the draft sills which receives the maximum buffering stresses.

70 It will be noted that the outer end portions of the bottom flanges 40^a of the rails 1, are cut away, as shown in Fig. 1, where the draft sill 2 laps said rails. The object of this is to permit the rivet connection between the rails 1 and said draft sills 2, as shown in Fig. 1, and interposed between the draft sills and the webs of the rails 1 are the members 54, before referred to, but as 85 said members 54 do not extend inwardly as far as the draft sills, filler blocks 54^a are provided which are interposed between the webs of sills 1 and the inner extensions of the draft sills.

80 90 95

95 Bolted or otherwise secured to the side sills 11, are nailing strips 60 upon which rest the outer ends of the floor 61, the said floor being supported intermediate the side sills by other nailing strips 62, as shown. The side sheathing 63 laps the nailing strip 60 and is secured directly thereto.

100 Buffing and pulling stresses are transmitted through a buffering column comprising the draft sills, bolster-center-filler-casting 105 and rails, and to assist said rails in supporting their proper proportion of the loading, truss rods extend from bolster to bolster, struts being interposed between said truss rods and the rails. The draft sills may vary 110 but are preferably about twelve inches in depth, while the rails are indicated as of conventional A. R. A. standard one hundred pounds per yard and of lesser depth.

110

115 What I claim is:

1. In combination in a railway car underframe, center sills of truss formation including spaced railway rails, struts and truss rods; draft sills connected with said rails and a bolster-center-filler casting upon which rest end portions of said rails.
2. In combination in a railway car underframe, center sills of truss formation including spaced railway rails, struts and truss rods; spaced side sills in a plane higher than 125 said center sills, draft sills connected with said rails and alined therewith, and a bolster-center-filler-casting upon which rest end portions of said rails.
3. In combination in a railway car under- 130

- frame, Z-shaped draft sills, railway rails lapping said draft sills and comprising parts of center sills, a bolster part adapted to serve as an anchor for a truss rod and on which rest said rails and with which the rails and draft sills are directly connected.
4. In combination in a railway car under-frame, bolsters, a building column comprising draft sills of plate formation and rolled railway rails lapping and being connected with said draft sills intermediate said bolsters only.
5. In combination in a railway car under-frame, draft sills, a bolster part lapped by said draft sills and railway rails with vertically disposed webs and bottom flanges comprising parts of center sills lapping and being secured to said draft sills and bolster part, said rails being of less depth than said draft sills and being positioned vertically thereof at the draft sill portions that are adapted to receive maximum buffing stresses.
6. In combination in a railway car under-frame, end sills and spaced bolsters, Z-shaped draft sills extending past said end sills and bolsters, railway rails comprising parts of center sills and an inwardly extending bolster part on which rest said rails and with which the rails and draft sills are directly connected.
7. In combination in a railway car under-frame, end sills, bolsters and draft sills extending between and beyond said bolsters, rails and truss rods lapping and being connected, respectively, with the lower portions of said draft sills and with extensions of said bolsters below said rails.
8. In combination in a railway car under-frame, end sills, bolsters and draft sills, the latter extending inwardly beyond said bolsters and a trussed center sill comprising spaced compression members and tension members lapping the inner extensions of said draft sills and being connected, respectively, to said draft sills and to extensions of said bolsters below said compression members.
9. In combination in a railway car under-frame, bolsters each comprising an integral inner extension adapted to serve as a chair for the compression member of a trussed center sill and an anchor for a truss rod therebelow, of sill compression members resting on said chair and truss rods connected with said anchor below said compression member.
10. In combination in a railway car under-frame, bolsters each comprising an integral inner extension adapted to serve as a chair for the compression member of a trussed center sill and an anchor for a truss rod therebelow, of sill compression members resting on said chair, truss rods connected with said anchor below said compression member and sill compression members resting on said chair, truss rods connected with said anchor below said compression member, and draft sills directly secured to said compression members and said chair.
11. In combination in a railway car underframe, end sills, spaced body bolsters, each bolster being provided with an inwardly extending chair, draft sills extending from said end sills past said bolsters and being secured directly to said chairs and trussed center sills terminating intermediate said bolsters and comprising compression members resting on said chairs and being connected with said draft sills and truss rods connected to said chairs.
12. In combination in a railway car underframe, end sills, body bolsters provided with chairs for center sill compression and tension members therebetween, draft sills extending from said end sills through and beyond said bolsters and being secured to said chairs, a center sill comprising spaced compression members secured upon said chairs and lapping said draft sills and truss rods secured at their ends directly to said chairs below the said compression members.
13. In combination in a railway car underframe, spaced center sills of truss formation including spaced compression members, struts and truss rods, draft sills connected with said compression members, and a bolster center filler casting upon which rest end portions of said compression members.
14. In combination in a railway car underframe, spaced body bolsters, center sills of truss formation including spaced rolled sections, struts and truss rods of less length than the distance between said bolsters, spaced side sills in a plane higher than said center sills, draft sills lapping and being connected with said rolled sections and alined therewith, and an extension projecting from each bolster upon which rest end portions of said rolled sections.
15. In combination in a railway car underframe, Z-shaped draft sills, center sill compression members lapping said draft sills, a bolster part adapted to serve as a seat for said compression members and as an anchor for a truss rod and draft sills connected with said compression members and said seat.
- In witness whereof I have hereunto set my hand in the presence of two witnesses. 120
